UNITED STATES PATENT OFFICE.

JULIUS B. WANTZ, OF OAK PARK, ILLINOIS, ASSIGNOR TO VICTOR X-RAY CORPORATION, OF CHICAGO, ILLINOIS, A CORPORATION OF NEW YORK.

X-RAY APPARATUS.

Application filed February 9, 1921. Serial No. 443,554.

My invention relates generally to X-ray apparatus for supporting in movable condition relative to a patient, an X-ray tube and its cooperating element, as for example 5 a fluorescent screen; my invention relating, more particularly, to apparatus intended for use in the setting of broken bones and in the fluoroscopic examination, or radiographing, of patients while in the condition 10 of pneumoperitoneum, a condition produced, generally stated, by the introduction of gas, such as oxygen, into the peritoneal cavity to effect distention of the walls of this cavity, for a purpose well known in the art. 15 In connection with the particular operations referred to, it may be stated that it is highly desirable that the X-rays be directed through the patient throughout a range of widely differing angles without disturbing 20 the patient and from a source the distance between which and the portion of the patient to be observed, or radiographed, remains a constant.

My objects, generally stated, are to provide 25 a construction of apparatus wherein provision is made for thus manipulating an X-ray tube and its cooperating element, as for example, and more particularly, a fluorescent screen, preferably so that these 30 parts at opposite sides of the patient may move in unison in a curved path and maintain in their different positions of adjustment throughout such path the desired relationship to each other and to the patient. 35 - As I have devised my improvements for use more particularly in connection with fluoroscopy, I have chosen to show my improvements in a machine adapted for this work, though without wishing to be understood as thereby intending to limit the invention.

Referring to the accompanying drawings:-

Figure 1 is a view in end elevation of an 45 apparatus constructed in accordance with my invention. Figure 2 is a view in side elevation of the same, viewing the apparatus from the right hand side of Fig. 1. Figure 3 is a view in elevation of the movable frame on which the X-ray tube and the fluorescent screen are supported, the

structure shown being viewed from the right hand side in Fig. 1 and shown as enlarged; and Figure 4, a view in side elevation of the structure shown in Fig. 3.

55

The apparatus, as shown, is formed of a base member 5 of general U-shape affording the lateral projections 6 at its ends, at which base the apparatus is adapted to be firmly supported on the floor. Rising from the 60 base 5 preferably midway between its ends is a standard 7 supporting at its upper end, a table, of material transparent to X-rays, for the patient, this table which extends laterally from the standard 7, being shown 65

as pivoted midway between its ends to the standard, as by means of the pivoting shaft 9 journaled in the upper end of the standard, the table 8 being provided toward opposite ends with handles 10 to facilitate the 70 rocking of the table on its pivot. The table 8 is provided with a depending portion 11 containing an arc-shaped slot 12 into which a stud 13 carried by the standard 7, projects, the outer end of this stud being pro- 75

vided with any suitable means for presenting, to the swinging movement of the table 8 upon its pivot 9, a desirable degree of friction, these means as shown comprising a friction disk 14 at one side of the projec- 80

tion 11 and a nut and spring washer 15 and 16, respectively, at the other side of the projection 11. The lower edge of the projection 11 is in the form of a segmental rack 17 which cooperates with a vertically mov- 85

able rod 18 guidingly confined in an ear 19 projecting horizontally from the standard 7 and in a bracket 20 carried by the base, this rod being provided with a pedal 21 for depressing it out of interlocking engage- 90

ment at its upper end with the notched portion of the rack 17, against the resistance of a coil spring 22 surrounding this rod be- 95

between the pedal 21 and the bracket 20, the purpose of this rod and rack being to hold the table 8 in the position to which it is adjusted on its pivot 9. Rising from the portion 6 of the base, are two pairs of lugs 23 supporting parallel guide rails 24 held thereto by means of cap plates 25, these rails 100 forming the support and guides for a frame, represented at 26 serving as the support for

the tube and screen-supporting mechanism. The support just referred to is formed of the end members 27 connected together by cross-brace 28 at their lower ends and a cross rod 29 at their upper laterally deflected ends. The members 27 are preferably of the form shown to provide the relatively wide base portions from which rise the portions 30 terminating in arc-shaped portions 31, the latter being provided with rollers 32 and 33 at their outer edges and with rollers 34 at their inner edges. The supporting structure thus provided carries at its lower end, grooved rollers 35 and 36 located, respectively, above and below the guide rails 24 and serving to permit this supporting structure to be moved lengthwise of the guide rails, but without danger of displacement thereon.

20 The primary support for an X-ray tube represented at 37 and the fluorescent screen represented at 38, in the particular construction illustrated, is in the form of a framework comprising the arc-shaped tubes 39 connected together adjacent their opposite ends by cross members 40 and 41 and intermediate their ends by cross-members 42 and 42^a, the frame thus provided extending at its curved members 39 into engagement with the rollers 32, 33 and 34, as shown, the rollers 32 and 33 extending at one side of each of the members 39 and the rollers 34 at the opposite side thereof and affording means whereby when the frame just referred to is moved up or down, it will move in a curved path corresponding with the curvature of its frame members 39, the parts of the apparatus being so positioned and arranged, as shown, that the movement of the frame is in a plane 40 extending transversely of, preferably at a right angle to, the longitudinal axis of the table 8. The frame just described is provided with a pair of rods 43 connected at their opposite ends with the cross members 41 and 42 and extending preferably at right angles thereto, these rods forming guide-ways for a support 44 in the form of a plate, for supporting the X-ray tube 37 and shutter mechanism hereinafter referred to, this plate being provided with apertured lugs 45 through which the rods 43 extend. The plate 44 is centrally apertured as indicated at 46, and at opposite sides, at one face thereof, is provided with bracket arms 47 spaced 55 apart and in which the X-ray tube 37 is adapted to be held in a manner well understood in the art, the tube being enclosed within a shield 48 which may be, by way of example, of a form commonly made of lead glass, for shielding the operator from the X-rays emitted from the tube and preferably opaque to ordinary light rays, as by coating it with black enamel. The tube shown is of the so-called Coolidge type em-

ploying high potential current for producing the X-rays and a low potential current for energizing the heating coil of the tube, one of the high tension wires represented at 49 being connected with the terminal 50 of the tube and the two wires 51 and 52 through 55 which the low tension current is supplied to the heating element of the tube and over one of which the high potential current flows, leading to a plug 53 for making the desired contacts with the tube in accordance with common practice, the wire 49 being shown as engaging the outer end of an insulating arm 54 connected with the bar 41 and thence extending in wound condition upon the reel 55 supported on a bar 56 of 60 insulating material connected at its ends with brackets 57 rising from the base portions of the members 26, this reel being connected with one of the wires of the high potential circuit, in a manner not shown 65 but which is well known in the art. The wires 51 and 52 likewise extend over insulating arms 58 carried by the cross-bar 41, and engage reels 59 and 60, respectively, upon which they are wound, these reels being supported on the bar 56 in insulated condition from each other, one of the wires 51 being connected with the other of the wires leading from the source of high potential current, this wire and the other of 70 the wires 51 and 52 being connected with any suitable source of low potential current, in a manner not shown but as will be understood by those skilled in the art.

75 The tube-carrying plate 44 cooperates with means through the medium of which it may be adjusted lengthwise of the rods 43, these means in the particular construction shown comprising a bar 61 carried by the plate 44 and equipped with a rack portion 62, the teeth of which mesh with a pinion 63 journaled in a lug 64 carried by the cross-bar 42, this pinion being rigidly connected with one end of a flexible shaft 65 which extends into the cross-bar 42 and at 80 its opposite end extends into one of the frame members 39, this end of the flexible shaft terminating in a knob 66 journaled on a boss 67 at the upper end of the said frame member 39, through the medium of which flexible shaft, the pinion 63 may be rotated for shifting the plate 44 along the guide rods 43. The plate 44 is also shown as provided with shutter-plates for increasing, or diminishing the size of the opening through which the rays emitted from the X-ray tube pass to the patient imposed on the table 8. The general construction of the shutter mechanism shown is that illustrated and described in United States Letters Patent No. 1,242,498 granted October 9, 1917, to J. B. Wantz, and thus detail description thereof is not necessary. It may be stated, however,

that the shutter mechanism as shown comprises a pair of plates 68 and 69 extending parallel to each other and supported, each at one end, on bars 70 and 71, respectively, 5 which are guided, to have lengthwise movement, by rollers 72 and 73 on the plate 44, these shutter plates being located adjacent one face of the plate 44 and moving, in the movement of the rods 70 and 71 in opposite 10 directions, toward and away from each other. The simultaneous movement of the rods 70 and 71 is effected by means of a rock lever 74 pivoted between its ends at 75 on the plate 44 and having pin and slot engagement 15 as indicated at 76, with adjacent portions of the bars 70 and 71, the lever 74 having pin and slot connection at 77 with a longitudinally movable bar 78 extending at right angles to the bars 70 and 71 and 20 guidingly confined on the member 44 by rollers 79 thereon. The upper end of the bar 78 is provided with a rack 80, with the teeth of which a pinion 81 meshes, this pinion being journaled in a lug 82 on the cross-member 25 42, this pinion being connected with a flexible shaft 83 extending through a lug 84 on the cross member 42 and through a sheathing 85 which lies within a portion of the one of the members 39 other than the one 30 containing the flexible shaft 65, the outer end of the shaft 83 being rigidly connected with a hand wheel 86 journaled in a stud 87 on the frame member 39. The other two shutter plates of the shutter mechanism are 35 represented at 88 and 89, these plates being at the rear side of the support 44 and connected with longitudinally movable rods represented at 90 and 91, these rods being connected together by a rock lever 92 pivoted 40 between its ends at 93 to the plate 44 and having pin and slot connection at 94 and 95 with the rods 90 and 91, whereby said rods move lengthwise simultaneously, but in the opposite direction upon lengthwise moving 45 of the bar 90, the upper end of which is in the form of a rack 96, it being noted that the plates 88 and 89 move in a path at a right angle to the path through which the plates 68 and 69 move, and that by the adjustment 50 of these plates the size of the opening presented therebetween and through which the X-rays pass from the tube, to the patient, may be increased or diminished as desired. The rack 96 meshes with a pinion 97 journaled in a lug 98 on the cross-bar 42, this pinion being rigidly connected with one end of a flexible shaft 99 extending into a sheathing 100 and lying within the adjacent one 55 of the side members 39, this flexible shaft 60 being connected at its outer end with a hand wheel 101 rotatable in a boss 102 on the member 39. The two hand wheels 86 and 101 thereby serve to afford independently operable means, operated by the operator, for independently moving the shutter plates of the

pairs thereof hereinbefore described, toward and away from each other to vary the size and shape of the opening through which the X-rays pass in their movement toward the patient. 70

The fluorescent screen 38 is mounted in a frame 103 preferably trunnioned at 104 to the arms 105 of a yoke-shaped frame 106 swiveled midway between its ends, as indicated at 107, to a supporting frame 108. 75 The opposite side members of this frame shown as formed of rods 109 are guidingly confined in slide bearings 110, with a set-screw 111 on one of these bearings for holding the frame 108 in adjusted position, these 80 slide bearings being adjustable lengthwise along a pair of parallel supporting guiding rods 112. One end of each rod is connected with the cross-member 40 and extends rearwardly and downwardly as shown, these 85 rods being connected with elbows 113 connected with rods 114, the latter being connected with the cross-member 42^a. One of the guide members 112 is provided with a set-screw 115 whereby these guide bearings 90 which are rigidly connected together by a bar 116 may be held in adjusted position on the rods 112.

From the foregoing description, it will be readily understood that in the use of the apparatus the operator, without disturbing the relative positions of the X-ray tube and the fluorescent screen, and without changing the position of the patient on the table, may, by moving the frame described and in part 95 formed of the tubes 39 along the rollers 32, 33 and 34, thereby causing this frame to move in a curved path, cause the X-rays to be directed against the patient from different angles about a given point as a center, which is of great advantage in the setting of bones and the fluoroscopic examination, or radiographing, of organs, especially when the patient is in the condition of pneumoperitoneum, and may also cause the patient 100 to extend at any desired angle to the vertical by tilting the table 8. In the particular arrangement shown the framework referred to and supporting the X-ray tube and fluorescent screen may be moved in the circular 105 path referred to throughout an arc of 90° or more, the rollers 32, 33 and 34 and the said frame-work being so proportioned as to present a degree of friction causing this movable framework to remain in the position to which it is moved by the operator, while permitting relatively easy movement of such framework, and the friction presented at the pivot of the table while preventing 110 too ready swinging of the table in case of unbalanced weight thereon, permits the operator to swing the table to the desired angle. 115

As a means for limiting the rotation of the said framework to the left in Fig. 1, stops, represented at 117 are provided on 120 125

4
this framework for engagement with the stationary frame sections 26.

It may be further stated that by this arrangement the X-ray tube and screen move as a unit in the shifting of the framework carrying them, the apparatus as shown permitting of the adjustment of the fluorescent screen, on the rods 112, into and out of a position in which it is diametrically opposed to the X-ray tube.

The other adjustments described and illustrated are also of value in connection with apparatus of this character; thus the adjustable mounting of the plate 44 on the rods 43 permit this plate, and with it the X-ray tube, to be adjusted, by means of the rack and pinion mechanism described, into different positions along these rods and consequently along the movable frame; the adjustable mounting of the shutters on the plate 44 permit of the increasing or diminishing, and the changing of the shape, of the opening through which the X-rays are directed by the tube against the patient; the mounting of the relatively stationary frame formed in part of the members 26, on the rods 24, permit of the adjustment of this frame, and the parts carried thereby, in a direction lengthwise of the table and consequently relative to the patient; and the adjustment of the table 8, as by the operator turning it upon its pivot 9, following the release of the rod 18 from the teeth of the rack 17, permits of the positioning of the patient at any desired angle relative to the vertical.

It may be further stated that the various relative movements of the several parts as described, causes the apparatus to lend itself to the quick and effective shifting of the various parts thereof, under perfect control of the operator and with the minimum amount of work and inconvenience to him.

While I have illustrated and described a particular embodiment of my invention, I do not wish to be understood as intending to limit it thereto as the same may be variously modified and altered without departing from the spirit of my invention.

What I claim as new, and desire to secure by Letters Patent, is:

1. In X-ray apparatus, the combination of a support presenting a guide of segmental circular shape presenting circular curvature lengthwise thereof, and a member for supporting an X-ray tube and a fluorescent screen or radiographic plate, engaging said guide and movable along the latter in an arc-shaped path, said tube and screen or plate being diametrically opposed at opposite sides of the center about which the arc of said guide is described.

2. In X-ray apparatus, the combination of a table, a support presenting a guide of segmental circular shape presenting circular curvature lengthwise thereof and extending

in a plane crosswise of the longitudinal axis of said table, with the center of the arc described by said guide being located in a plane between the planes in which the sides of said table extend, and a member for supporting an X-ray tube and a fluorescent screen or radiographic plate, engaging said guide and movable along the latter in an arc-shaped path, said tube and screen or plate being diametrically opposed at opposite sides of the center about which the arc of said guide is described.

3. In X-ray apparatus, the combination of a support presenting a guide curved lengthwise thereof, a member supporting an X-ray tube, said member engaging said guide and being movable along the latter in a curved path and formed of sections one of which engages said guide and the other of which carries said tube and is adjustable on said first-referred-to section in a direction tangentially of said guide to vary the position of said tube on the guide-engaging one of said sections, and a support for the patient, said member being movable along said guide independently of said last-named support.

4. In X-ray apparatus, the combination of a plurality of members, an X-ray tube on one of said members, said last-referred-to member being confined on the other of said members to move in a curved path and formed of sections one of which engages said last-named member and the other of which carries said tube and is adjustable on said first-referred-to section in a direction tangentially of said curved path to vary the position of said tube on said first-referred-to section, and a support for the patient, the one of said members carrying said tube being movable along the other of said members independently of said support.

5. In X-ray apparatus, the combination of a support presenting a guide curved lengthwise thereof, a member for supporting an X-ray tube and a fluorescent screen, or radiographic plate, engaging said guide and movable along the latter in an arc-shaped path, said member being formed with a holder for said screen, or radiographic plate, adjustable relative to the main portion of said member, said tube and screen, or plate, being diametrically opposed at opposite sides of the center about which the arc of said guide is described, and a support for the patient, said member being movable along said guide independently of said last named support.

6. In X-ray apparatus, the combination of a support presenting a guide curved lengthwise thereof, a member for supporting an X-ray tube and a fluorescent screen, or radiographic plate, engaging said guide and movable thereon in an arc-shaped path and having a holder-portion at which said screen,

- or plate, is carried adjustable to vary the position of said screen, or plate, on said member, said tube and screen, or plate, being diametrically opposed at opposite sides 5 of the center about which the arc of said guide is described, and a support for the patient, the one of said members carrying said tube being movable on the other thereof independently of said last-named support.
- 10 7. In X-ray apparatus, the combination of a support presenting a guide curved lengthwise thereof, a member for supporting an X-ray tube and a fluorescent screen, or radiographic plate, engaging said guide and movable along the latter in an arc-shaped path, said member being formed with a holder for said screen, or radiographic plate, adjustable relative to the main portion of the member, and with a portion for holding 15 the X-ray tube adjustable relative to the body of said member, said tube and screen, or plate, being diametrically opposed at opposite sides of the center about which the arc of said guide is described, and a support 20 for the patient, said member being movable along said guide independently of said last-named support.
8. In X-ray apparatus, the combination of a support presenting a guide curved lengthwise thereof, a member supporting an X-ray tube, said member engaging said guide and being movable along the latter in a curved path and formed of sections one of which engages said guide and the other of which 25 carries said tube and is adjustable on said first-referred-to section in a direction tangentially of said guide to vary the position of said tube on the guide-engaging one of said sections, and a support for the patient, 30 the one of said members carrying said tube being movable on the other thereof independently of said last-named support.
9. In X-ray apparatus, the combination of a movably-supported member, a holder device for an X-ray tube adjustably mounted 35 on said member, an adjustable shutter device operatively connected with said holder and movable therewith in the adjustment of the latter, and means for adjusting said 40 shutter device involving a part supported on said member and with relation to which said shutter device is movable, said means being constructed and arranged to permit said holder to be moved into different positions, and with it said shutter device, without disturbing the adjustment of the shutter device relative to the holder.
10. In X-ray apparatus, the combination of a movably-supported member, a holder device for an X-ray tube adjustably mounted 45 on said member, an adjustable shutter device operatively connected with said holder and movable therewith in the adjustment of the latter, and means for adjusting said 50 shutter device involving a flexible shaft on said member, means on said member and connected with said flexible shaft for rotating the latter, and means connecting said flexible shaft with said shutter device, constructed and arranged to permit said holder 70 to be moved into different positions and with it said shutter device without disturbing the adjustment of said shutter device relative to said holder.
11. In X-ray apparatus, the combination 75 of a movably-supported member, a holder device for an X-ray tube adjustably mounted on said member, an adjustable shutter device operatively connected with said holder and movable therewith in the adjustment of the latter, and means for adjusting said shutter device involving rack and pinion mechanism operatively connected with said shutter device, a flexible shaft connected with said pinion and carried by said member, and 80 means on said member for rotating said flexible shaft.
12. In X-ray apparatus, the combination 85 of a plurality of members, and an X-ray tube and a fluorescent screen, or radiographic plate, on one of said members, said last-referred-to member being confined on the other of said members to move in an arc-shaped path, said tube and screen, or plate, being located at opposite sides of the 90 center about which said arc is described.
13. In X-ray apparatus, the combination 95 of a plurality of members, an X-ray tube and a fluorescent screen, or radiographic plate, on one of said members, said last-referred-to member being confined on the other of said members to move in an arc-shaped path, said tube and screen, or plate, being located at opposite sides of the center 100 about which the said arc is described and a support for the patient, said last-referred-to member being movable lengthwise of said support in a path at an angle to the plane of said arc-shaped path.
14. In X-ray apparatus, the combination 110 of a support for a patient, and a plurality of members one for supporting an X-ray tube and a fluorescent screen, or radiographic plate, said last-referred-to member being movable on the other of said members in a curved path, to a position in which said tube extends below that portion of said support upon which the patient rests, said tube and screen, or plate, extending at opposite 115 sides of the center about which said arc is described.
15. In X-ray apparatus, the combination 120 of a support for a patient, and a plurality of members one for supporting an X-ray tube and a fluorescent screen, or radiographic plate, said last-referred-to member being movable on the other of said members in a curved path to a position in which said tube extends below that portion of said support upon which the patient rests, said tube 125 130

- and screen, or plate, being diametrically opposed relative to the center about which said arc is described.
16. In X-ray apparatus, the combination of a member for supporting an X-ray tube and a fluorescent screen, or radiographic plate, and means supporting said member to move in an arc-shaped path, said tube and screen, or plate, being located at opposite sides of the center about which said arc is described. 70
17. In X-ray apparatus, the combination of a support for a patient, and a plurality of members one for supporting an X-ray tube and a fluorescent screen, or radiographic plate, said last-referred-to members being movable on the other of said members, in an arc-shaped path, said tube and screen, or plate, being located at opposite sides of the center about which said arc is described, and said last-referred-to member being movable in said arc-shaped path to a position in which said tube extends below that portion of the support upon which the patient rests. 75
18. In X-ray apparatus, the combination of a plurality of members, and an X-ray tube and a fluorescent screen, or radiographic plate, on one of said members, said last-referred-to member being confined on the other of said members to move in an arc-shaped path, said tube and screen, or plate, being diametrically opposed relative to the center about which said arc is described. 80
19. In X-ray apparatus, the combination of a member upon which the patient is supported, means supporting said member and adapting it to be tilted into different positions, a plurality of members adjacent said first-named-member, and an X-ray tube and a fluorescent screen, or radiographic plate, on one of said plurality of members, said last-referred-to member being movable on the other of said plurality of members in a curved path. 85
20. In X-ray apparatus, the combination of a member upon which the patient is supported, means supporting said member and adapting it to be tilted into different positions, a plurality of members adjacent said first-named-member, and an X-ray tube and a fluorescent screen, or radiographic plate, on one of said plurality of members, said last-referred-to member being movable on the other of said plurality of members in an arc-shaped path, the center of the arc described by said path, being above said first-referred-to member and between the sides of the latter. 90
21. In X-ray apparatus, the combination of a member upon which the patient is supported, means supporting said member and adapting it to be tilted into different positions, a plurality of members adjacent said first-named-member, and an X-ray tube and a fluorescent screen, or radiographic plate, on one of said plurality of members, said last-referred-to member being movable on the other of said plurality of members in a curved path, extending crosswise of the longitudinal axis of said first-named-member. 95
22. In X-ray apparatus, the combination of a table, and an X-ray tube-holder, a holder for a fluorescent screen, or radiographic plate, means supporting said holders for rotation as a unit about a point above the table top as a center, and means supporting the top of said table for movement into different angular positions relative to said holders. 100
23. In X-ray apparatus, the combination of a table, and an X-ray tube-holder, a holder for a fluorescent screen, or radiographic plate, means supporting said holders for rotation as a unit about a point above the table top as a center, and means supporting the top of said table for movement into different angular positions in a plane extending crosswise of the axis about which said holders rotate. 105
24. In X-ray apparatus, the combination of a table for supporting a patient, a plurality of cooperating members one of which forms a support, an X-ray tube and fluorescent screen, or radiographic plate, on the other of said members, said supporting member extending at one side only of said table and said other member being movable on said supporting member in an arc-shaped path to a position in which said tube extends beneath, and said screen, or plate, above, said table, said tube and screen, or plate, being diametrically opposed at opposite sides of the center about which the arc of said guide is described. 110
25. In X-ray apparatus, the combination of a support for a patient, and a plurality of members, one for supporting an X-ray tube and a fluorescent screen, or radiographic plate, said last-referred-to member being movable on the other of said members in an arc-shaped path throughout substantially 90 degrees from a position in which said tube extends substantially directly below said support to a position in which it extends substantially along the side of said support, said tube and screen, or plate, being diametrically opposed at opposite sides of the center about which the arc of said guide is described. 115
26. In X-ray apparatus, the combination of a table for supporting a patient, a plurality of co-operating members one of which forms a support, an X-ray tube and fluorescent screen, or radiographic plate, on the other of said members, said supporting member extending at one side only of said table and said other member being movable on said supporting member in an arc-shaped 120
- 125
- 130

- path throughout substantially 90 degrees from a position in which said tube extends substantially directly below said table and said screen, or plate, substantially above said table to a position in which said tube and screen, or plate, extend substantially along the sides of said support, said tube and screen, or plate, being diametrically opposed at opposite sides of the center about which the arc of said guide is described. 20
- 5 25
27. In X-ray apparatus, the combination of a support for a patient tilttable in the direction of its length, a second support presenting a guide of segmental circular shape 10
- 15 30
- presenting circular curvature lengthwise thereof, and a member for supporting an X-ray tube and a fluorescent screen, or radiographic plate, engaging said guide and movable along the latter in an arc-shaped 35
- path, said tube and screen, or plate, being diametrically opposed at opposite sides of the center about which the arc of said guide is described. 20
- 25
28. In X-ray apparatus, the combination of a plurality of members, an X-ray tube and a fluorescent screen, or radiographic plate, on one of said members, said last referred to member being confined on the other of said members to move in an arc-shaped path, said tube and screen, or plate, being diametrically opposed at opposite sides of the center about which the arc of said guide is described. 30
